FOLDABLE COMBINATION ASH TRAY

Carl A. Gottfried, Grand Rapids, Mich.

Application December 28, 1931, Serial No. 583,575

13 Claims. (Cl. 131—51)

This invention relates to an ash receptacle and is primarily concerned with a receptacle which is of simple and economical construction, which normally is closed, which can be opened readily 5 to receive ashes or the butts of cigars and cigarettes and from which the ashes or other refuse may be readily removed. There may also be incorporated in connection with the ash receptacle and inclosed therein a further receptacle for holding matches in a readily and easily accessible and 10 convenient location.

The invention may be understood from the following description, taken in connection with the accompanying drawing, in which,

15 Fig. 1 is a perspective view of the ash receptacle of my invention showing the same closed.

Fig. 2 is an enlarged front elevation, with parts at the lower end broken away and shown in section, and with the ash receptacle open to receive 20 ashes or cigar or cigarette butts.

Fig. 3 is a vertical section on the plane of line 3—3 of Fig. 2.

Fig. 4 is a similar vertical section showing the receptacle in closed position.

25 Fig. 5 is a plan view of the receptacle in open position, as in Figs. 2 and 3.

Fig. 6 is a horizontal section on the plane of line 6—6 of Fig. 4, and

Fig. 7 is a horizontal section on the plane of 30 line 7—7 of Fig. 2.

Like reference characters refer to like parts in the different figures of the drawing.

In the construction of the receptacle, which is made preferably from sheet metal, a vertical front 35 1 is provided from which, at its lower end, a bottom 2 extends to the rear and is then extended upwardly as a vertical back 3 for a distance above the upper edge of the front 1. The metal of the back 3 may be continued and bent back 40 upon itself to form the rear side 4 of a match holding receptacle, the bottom 5 of which extends forward from the lower edge of the back 4 and terminates in a vertical front 6 which, for a whole or a part of its length, may be vertically 45 ribbed or corrugated as indicated at 6a. Ends 7 complete the match receptacle and sides 8 extending between the front and back 1 and 3 of the ash receptacle and to the upper end of the back 3 are used to complete said ash receptacle except 50 for its upper closing members. The sheet metal sides, front, back and bottom may be connected together in any preferred manner and whether or not the parts 1, 2, 3, 4, 5 and 6 are made of a continuous length of sheet metal is not important 55 as they may be made from one or more pieces of

sheet metal suitably secured together so as to be in effect integral.

In the bottom 2 of the ash receptacle openings are made and around the same downwardly extending threaded sleeves 9 are located. On said sleeves closing caps 10 are threaded as best shown in Fig. 2. Also within the receptacle and resting upon the bottom is a sheet metal plate 11 formed as shown so as to direct ashes or other refuse toward said openings and into the sleeves 9 where- 10 by on removing the caps 10 the ashes and other refuse drops freely by gravity from the ash receptacle and none of it is held in corners thereof.

A closing lid 12 of an inverted shallow pan-like form is provided and is hingedly connected at 13 15 at the upper end of the back 3. A spring 14 around the hinge pintle and bearing against the lid and the back 3 serves normally to throw the lid to upper vertical position, as shown in Fig. 3, when free to do so.

20 A hinged extension 15 to the front 1 is provided from the side edges of which side members 16 extend rearwardly. This extension member is pivotally connected at 17 to the upper edge of the front 1 and a coiled spring 18 is associated with 25 the hinge pintle and the parts 1 and 15, the effect of which is to normally move the extension front 15 and the parts connected thereto to an outer position as shown in Fig. 3.

20 A plurality of holders 19 are secured at the 30 inner side of the extension front 15 and preferably are of a substantially semi-cylindrical form located one alongside of each other and made from a single length of sheet metal. At the back 3 a suitable projection 20 is pressed inwardly so 35 as to limit the extent of opening of said upper extension front member and the ends of the sides 16 are preferably cut at an angle, as indicated at 16a, so as to come against the back 3 when in such position.

40 Cooperating latching members 21 and 22 are provided on the extension front 15 and the front depending side of the lid 12 whereby the two, when connected together, as shown in Fig. 4, will cause the lid 12 to be held in closed position 45 and the front member 15 in vertical position; but by pressing inwardly on the part 21 the latch member may be disengaged whereupon the lid will automatically be thrown to its vertical position, shown in Fig. 3, and the extension front 50 member 15 with the attached parts moved to its outer inclined position, also shown in Fig. 3.

55 Lugs 23 may be welded or otherwise secured to the back 3 for the purpose of attaching the appliance to a vertical support such as the dash of

an automobile. As previously stated by pressing inwardly on the latch member 21 the receptacle is opened and the parts occupy the position shown in Fig. 3. The matches held within the match receptacle are thereupon accessible and ashes, matches or the like may be inserted in the receptacle through the members 19 and underneath the match holder; and when it is desired, a cigar or cigarette may be placed in one of the holders 19 as indicated in dotted lines (Figs. 3 and 5). The appliance may be closed whenever desired, the latching devices 21 and 22 holding the same in closed position. Also, often-times it is desirable to flick the ashes from the cigars and this may be done by a slight upward movement on the outer underside of the front 15 with a quick release to permit the spring 18 to snap the front downwardly thus causing an abrupt stop which serves the aforesaid purpose, the bottom 5 serving as a stop to prevent displacement of the cigars. The ashes drop downwardly through the cut away portion as clearly shown in Fig. 3.

As shown in the drawing, the spring 14 urges the lid 12 upwardly but if desired, the spring 14 may be reversed so that the same will cause the lid 12 to remain closed at all times. Or, if desired, the spring 14 may be entirely omitted and gravity will act upon the lid 12 or else the hinge 30 13 will frictionally maintain the lid 12 in any desired position.

If the spring 14 tends to keep the lid 12 closed, the upper curved portion of the element 15 cams against the underside of the lid when the same is pushed to a closed position, see Fig. 4, and hence an initial opening movement is given to the lid 12.

The lid 12 is shown as overlapping the side members 8 but I deem it to be within the purview 40 of my invention to make the lid of such length as to have the depending ends thereof lie immediately above the side members 8 and abut the same, the side members 8 being cut away when this construction is used.

I also deem it to be within the scope of my invention to utilize only a single cigarette containing member 19 and also lengthen the lower portion of the container 1 so that when desired a quantity of ashes may be held therein.

In some cases, such as when used in railway cars, it is advisable to construct the device of cast iron and provide a depending outlet from the lower part of the box leading to the exterior of the car. Also, the match box container 5 may be dispensed with if desired.

The device described is of a very practical and effective construction. Ashes placed upon the parts 19 or matches or cigars or cigarette butts placed thereon are dumped into the main receptacle on closing; or when open the vibration of an automobile with which the device is used causes the same to move inwardly and fall to the bottom of the receptacle.

The invention is defined in the appended 65 claims and is to be considered comprehensive of all forms of structure coming within their scope.

I claim:

1. A receptacle having back, bottom and sides and a fixed front shorter than the back, a lid for closing the upper end of the receptacle, an extension front pivotally connected to the upper edge of the said front, said extension extending both within and without the confines of the receptacle when in one of its positions, said extension setting on an angle in said position, the in-

ner end being the lower, whereby ashes thereon will gravitate to the rear of said extension.

2. A construction containing the elements in combination defined in claim 1, said extension front having sides thereto extending inwardly and adapted to engage against the back of the receptacle and limit the outward turning movement thereof. 5

3. A construction containing the elements in combination defined in claim 1, said extension front having a plurality of holders located at the inner side of said extension front of concavo-convex form. 10

4. In combination, a box having an upper open end, a flat member pivoted to the upper edge of said box, said flat member being adapted to receive cigarettes or the like, said flat member having sides thereto extending inwardly and abutting against the back of the box when it is in its operative position, said operative position being an angular position, the inner end being lowermost, whereby ashes will gravitate to the rear of said flat member, the flat member being cut away to permit the ashes to fall into the box. 15 20

5. In an ash container having its upper end open, the combination of, a cigarette supporting element pivotally attached to the container at the upper edge of the front side of the container, said element extending both without and within the confines of the container when it is in one of its positions, said container extending downwardly from the pivot of said cigarette supporting element to form a receptacle thereunder for the purpose described, and a stationary shielding member located over the inner end 30 of said supporting element when it is located in the above referred to position. 35

6. In combination, a box-like container having an open end, a removable closure for its lower end, a lid pivoted to its upper end to close the same as desired, said container having one of its sides partly cut away, a supporting element pivoted at a point along its length to the top edge of said cut away side, curved holding means fastened to the upper or inner side of said supporting element, said holding means being adapted to receive a cigarette or the like, and means on the lid member adapted to engage the supporting element whereby the box-like container may be held in closed position. 40 45 50

7. A receptacle having a back, bottom, sides and a fixed front shorter than the back, an inverted pan shaped lid for closing the upper end of the receptacle mounted at the top edge of the back member, a cigarette supporting element pivotally attached to the upper edge of the front member, said element extending both without and within the confines of the container when in open position, the outer downturned edge of said lid engaging the outer edge of said supporting element whereby they may be maintained in closed position. 55 60

8. In an ash receptacle of the class described, a container having its upper end open, a flat element hinged to the upper edge of the front side of the container, said flat element being movable to a position at an acute angle to horizontal when desired and said element extending both within and without the confines of the container when in operative position, the inner end 65 of said element being the lower end, said flat element serving to support cigarettes and the like at said angle whereby they and the ashes therefrom will gravitate to the lower end of said element when it is in said angular position and the 70 75 80

inner and lower end of said element extending inwardly toward the back of the container and being spaced from the back of the container whereby ashes may drop between said end of 5 the supporting element and the back of the container.

9. A construction containing the elements in combination defined in claim 7 but further characterized by the fact that the container has 10 openings leading from its bottom and separate closure means for each of said openings, said bottom converging inwardly and downwardly in a funnel shape toward each opening whereby ashes therein will gravitate into said openings.

15 10. A receptacle having a back, bottom and sides and a fixed front shorter than the back, a lid for closing the upper end of the receptacle, a cigar supporting element pivotally connected to the upper edge of the said front, said supporting element extending within the confines of the receptacle in one of its positions, said position being an acute angle to horizontal, the inner end of the supporting element being the lowest, whereby a cigar placed on said element will gravitate towards and against the back of the receptacle whereby relative movement between said element and said receptacle will cause the end of 25 the cigar to rub against said back causing ashes to be removed therefrom.

30 11. In combination, a container having a hinged upper lid, a cigarette supporting element hinged to the top of one of the sides of the container, said side being cut away, interengaging means between the cover member and the sup-

porting element whereby they may be maintained in closed position, a shielding member located between the cover member and the supporting element, said shielding member having an arcuate indentation at its front underside, said cigarette supporting element passing through said arcuate indentation in the shielding member when swung to its closed position. 5

12. In combination, a box having an open upper end, one side being shorter than the other, a 10 supporting element pivoted to the upper end of the short side of the box at a point intermediate the ends of the supporting element, one end of said element contacting the back of the box in one of its positions, and curved holding means 15 fastened to the upper side of the supporting element, said holding means being adapted to receive a cigarette or the like.

13. In combination, a container having a hinged upper lid, a cigarette supporting element 20 hinged to the top of one of the sides of the container, said side being cut away, interengaging means between the cover member and the supporting element whereby they may be maintained in closed position, said supporting element 25 being pivoted to the said cut away side member at a point between the ends of said supporting element, said supporting element having the portion which extends into the container spaced away from the back of said container to permit 30 ashes to fall between the same and the container.

CARL A. GOTTFRIED.
